INVENTOR
William H. Rose
BY *Horace F. Ladd*
his ATTORNEY

UNITED STATES PATENT OFFICE.

WILLIAM H. ROSE, OF JERSEY CITY, NEW JERSEY.

LIQUID-DISPENSING DEVICE.

Application filed November 4, 1924. Serial No. 747,878.

To all whom it may concern:

Be it known that I, WILLIAM H. ROSE, a citizen of the United States, residing at Jersey City, county of Hudson, and State 5 of New Jersey, have invented new and useful Improvements in Liquid-Dispensing Devices, of which the following is a full, clear, and exact specification.

My invention relates to liquid dispensing 10 devices and refers particularly to devices of this character of a construction particularly adapted for use with disinfectants.

It is frequently desirable to employ disinfectants in small quantities at predetermined 15 periods, the delivery of the disinfectant from a receptacle being caused either automatically or through manual manipulation.

The present employed methods for accomplishing 20 these results by means of absorbent wicks is not applicable to many disinfectants, because of the absence of proper capillary power of the wick, or because of the effect of the solution upon the wick, causing 25 the delivery of the liquid to be uncertain or entirely interrupted.

Devices of the wick character can not be employed with soluble soap disinfectants, which rapidly decrease the capillary properties 30 of the wick with the resultant discontinuance of disinfectant delivery.

My device overcomes these, and other, objectionable features of the present employed devices and presents a means whereby 35 disinfectants of the soluble soap class, and others, may be successfully applied.

My device includes a particularly formed 40 valve, or valves, of such construction as to retain the liquid within the receptacle when it is not in operation, but will allow of the escape of the liquid in quantities dependent upon the amount and duration of pressure applied to the liquid within the receptacle.

It is immaterial in the employment of my 45 device as to the source of pressure, which may be of manual, mechanical, electric, or other types, as the device may be regulated to operate successfully by any means which will allow of interrupted pressure upon the 50 receptacle contents.

The object of my invention, therefore, is a 55 liquid dispenser without wicks, or other elements depending upon capillary attraction, capable of the intermittent delivery of small quantities of liquids from a receptacle, the

delivery being caused by pressure upon the liquid within the receptacle, the device being applicable to soluble disinfectants of the soluble soap and other types of chemicals.

In the accompanying drawings illustrating 60 modified forms of the device of my invention, similar parts are designated by similar numerals.

Figure 1 is a view of one form of my device showing one means of its attachment to 65 a supply receptacle.

Figure 2 is a broken vertical cross-section of one form of my device.

Figure 3 is a broken vertical cross-section 70 of a modified form of my device.

Figure 4 is a broken vertical cross-section 75 of a modified form of my device showing means for attaching and retaining the disc valve member.

Figure 5 is a vertical cross-section showing 80 a modified form of pressure means.

The particular form of the device of my invention, shown in Figures 1 and 2, comprises an annular receptacle having the top 85 10 and the side 11. The side 11 carries the inwardly extended flange 12 thus forming an opening 13. The lower portion of the inner face of the side 11 is internally threaded to mesh with an externally threaded ring 14. The ring 14 and the flange 12 thus act 85 as a support for the rubber disc 15, producing a tight jointure. The disc 15 has a centrally positioned incision, or slot, 16, which remains closed under normal conditions but which may be opened to release 90 liquid from within the receptacle when pressure is exerted upon said liquid.

A tube 17 is threaded within the threaded opening 18 of the top 10 and is connected to the tube, or pipe, 19 by means of the 95 coupling 20, the tube 19 being connected to a supply receptacle 21, which need not be hermetically sealed by the lid 22. A tube 23 is threaded within a threaded opening of the receptacle and is connected to the pipe 100 24 by means of the coupling 25. The tube 24 is attached to the base plate 25', to which is attached the semi-spherical rubber pressure member 26 by means of the binding wire 27.

Within the tube 17 is a flap valve member 28 having the incision 29 forming a flap valve 30, the valve allowing the downward flow of liquid from the pipe 17 when in normal position but being closed when pressure 110

is exerted upon the under face of the flange valve 30.

In operation, the supply receptacle contains a liquid which flows downwardly through the pipe members filling the receptacle, the valve disc 15 preventing the liquid from passing therethrough. If the rubber member 26 be pressed, a pressure will be produced upon the liquid in the receptacle causing the flap valve 30 to close and the incision valve opening 16 to open, allowing the escape of liquid from the receptacle.

The design illustrated in Figure 3 is similar in construction to that described above, with the exception that the flap valve is omitted from the pipe 17 and the supply receptacle 21 is closed and air-tight. It will thus be seen that a pressure upon a rubber pressure member connected to the pipe 24 will cause the incision valve 15 to open and allow of the escape of liquid from the receptacle.

In the device shown in Figure 4, the valve disc 15 is retained in place by the angular member 31 threaded upon the outer face of the receptacle side 11 and having an opening 32 therein.

Figure 5 illustrates a convenient and efficient pressure bulb, comprising the base 32 and the cap 33 having an opening 34 therein, a hollow rubber member 35 rests upon the base 32 and has its push button 36 extended through the opening 34. The parts thereof may be so interrelated that the downward pressure of the member 36 until it is flush with the cap 33 will cause the release of a required quantity of liquid from the receptacle.

I do not limit myself to the particular size, shape, number, or arrangement of parts, as shown and described, as these are given simply as a means for clearly describing the device of my invention.

What I claim is:—

1. In a liquid dispensing device, in combination, a receptacle having an exit opening therein, a resilient member covering the exit opening and having a slit valve therein, the slit remaining normally closed but being capable of opening upon pressure exerted upon a liquid within the receptacle, means for retaining the slit valve over the exit opening, a liquid supply receptacle, a conduit connecting the supply receptacle to the receptacle, a conduit connecting the receptacle with an intermittent pressure exerting device and a device capable of exerting an

intermittent pressure upon a liquid within the receptacle.

2. In a liquid dispensing device, in combination, a receptacle having an exit opening therein, a resilient member covering the exit opening and having a slit valve therein, the slit remaining normally closed but being capable of opening upon pressure exerted upon a liquid within the receptacle, means for retaining the slit valve over the exit opening, a liquid supply receptacle, a conduit connecting the supply receptacle, a check valve carried by the conduit allowing the flow of liquid from the supply receptacle to the receptacle and preventing the return of the liquid when a pressure is exerted upon a liquid within the receptacle, a conduit connecting the receptacle with an intermittent pressure exerting device and a device capable of exerting an intermittent pressure upon a liquid within the receptacle.

3. In a liquid dispensing device, in combination, a receptacle having an exit opening therein, a resilient member covering the exit opening and having a slit valve therein, the slit remaining normally closed but being capable of opening upon pressure exerted upon a liquid within the receptacle, means for retaining the slit valve over the exit opening, a liquid supply receptacle, a conduit connecting the supply receptacle to the receptacle, a conduit connecting the receptacle with a hollow rubber member a pressure upon which will exert a pressure upon a liquid within the receptacle.

4. In a liquid dispensing device, in combination, a receptacle having an exit opening therein, a resilient member covering the exit opening and having a slit valve therein, the slit remaining normally closed but being capable of opening upon pressure exerted upon a liquid within the receptacle, means for retaining the slit valve over the exit opening, a liquid supply receptacle, a conduit connecting the supply receptacle to the receptacle, a check valve carried by the conduit allowing the flow of liquid from the supply receptacle to the receptacle and preventing the return of the liquid when a pressure is exerted upon a liquid within the receptacle, a conduit connecting the receptacle with a hollow rubber member a pressure upon which will exert a pressure upon a liquid within the receptacle.

Signed at New York city in the county of New York and State of New York this 30th day of October, 1924.

WILLIAM H. ROSE.
